UNITED STATES PATENT OFFICE.

GEORGE L. WESTMAN AND JOSEPH DELARUE, OF RICHMOND, VIRGINIA.

CIGAR-BUNCHING MACHINE.

SPECIFICATION forming part of Letters Patent No. 446,989, dated February 24, 1891.

Application filed November 16, 1889. Serial No. 330,267. (No model.)

To all whom it may concern:

Be it known that we, GEORGE L. WESTMAN and JOSEPH DELARUE, citizens of the United States of America, residing at Richmond, in the county of Henrico and State of Virginia, have invented certain new and useful Improvements in Cigar-Bunching Machines, of which the following is a specification, reference being had therein to the accompanying drawings.

Our invention relates to cigar-bunching machines; and the object of our improvements is, among other things, first, to provide a machine for forming what is known in the trade as "long-filler" cigars—that is, a cigar in which the filling runs lengthwise of the cigar and of the leaf; second, to provide a machine by which cigars may be formed of one uniform size and weight, and, third, to reduce wastage and loss in their manufacture to the lowest possible degree. We attain these objects by the use of the mechanism illustrated in the accompanying drawings, in which—

Figure 1 is a side elevation of our machine. Fig. 2 is a longitudinal sectional view of same. Fig. 3 is a cross-sectional view immediately in front of the rollers X and X'. Fig. 4 is an enlarged sectional view in detail of the mechanism denominated the "receiving-box," the "plunger," the "feed-belts," &c. Fig. 5 is a perspective view of the mechanism denominated the "packer," which consists of the parts G and G', the upper half G being the cover and the lower half G' being the bottom, each separate part being composed of a single curved longitudinal piece of metal having seamed edges and adapted to slide the one upon the other, G over and G' within upon said longitudinal edges, a section of the space inclosed between the top and bottom forming the outline plan of a cigar. The figure shows also the lower feed-belt G² and the frame C', to which the said packer is hinged. It will be seen that the packer is a longitudinal elliptical-shaped box, one end being closed, the cover G being free to be slipped longitudinally in either direction. Fig. 6 is a sectional detail drawing of the mechanism denominated the "receiving-box," detached from the machine and top plan view of part of the machine. Fig. 7 is a detail perspective view of the receiving-box from the side next the

rollers X and X', the follower and plunger removed.

Similar letters refer to similar parts throughout the several views.

A represents the legs of an iron table, and B top of same.

C and C' represent two frames, which are placed nearly parallel to each other, affording facilities for carrying the feed-belts.

We will first describe the frame C'. The side bars of the frame C' are supported upon standards attached to the table B near their centers, their ends next to the roller X' being hollowed out, as shown in Fig. 5, and adapted to rest upon and against the journals of said roller, their opposite ends carrying a roller journaled in slots and in movable slides, said slides being moved by the screws O' at the end of the frame to regulate the tension of said feed-belt. The upper frame C is an exact counterpart of the frame C' above described, but is not supported on standards. Its ends rest upon and against the journals X. Their opposite ends carry a roller journaled in slots and in movable slides adapted to be moved by the screws O at the end of the frame to regulate the tension of the feed-belt, the frame and belt resting upon the lower frame and belt and being free to swing against the journal of the roller X as a center, being held thereto by the tension of the feed-belt. Frame C may be raised and stood up out of the way against the frame R when the tobacco from the packer is being placed upon the lower feed-belt, and then it is laid down to hold the tobacco in place, upon which it will then rest, the tobacco being between the upper and lower feed-belts. Said feed-belts move in the same direction—viz., toward the rollers X and X'.

We will now describe the rollers X and X'. Said rollers are journaled in the upright frames R, one above the other. The journals of the lower roller X' are fixed and do not move up or down, while the journals of the upper roller X are journaled in movable boxes set in the side of said frames R and are connected with the screws T at the top of said upright frames, said screws being adapted to raise said boxes, by means of which the distance between the rollers and feed-belts may be regulated. The journals of the rollers ex-

tend through the sides of said upright frames R and are adapted to carry the cog-wheels O², keyed thereto, the journal of the opposite end of the lower roller X' being adapted to carry 5 the ratchet-wheel N', keyed thereto, upon which the pawl N² operates, as hereinafter described. The cog-wheels O² are adapted to engage each other in gear, and the movement of the ratchet-wheel N' will turn both rollers, 10 so that the respective belts in contact with the tobacco will move in the same direction, carrying the tobacco upon the cutting-ledge Y and through the open side into the receiving-box U, hereinafter described.

15 The ratchet-wheel N' is operated by the pawl N² on part Q, which is connected to the lever Q² by the bar Q', as shown. The lever Q² is attached to the side of the frame A, its lower end being bifurcated and resting in a 10 notch on the periphery or edge of the quadrant l. The rim of said quadrant acts as a guide and the notch engages the lever in the fork, the opposite end of said lever being connected by the bar Q' to the part Q, that carries the pawl N². As the quadrant is 25 revolved by pressing down the treadle, the lower end of said lever will be carried in the same direction with the quadrant until it slips from the notch, where it will remain stationary, the rim of the quadrant sliding in 30 the fork. The upper end of said lever will be thrown backward, and by means of the connecting-bar Q' will engage the part that carries the pawl N², which will actuate the 35 ratchet-wheel N', which in turn will move the cog-wheels O², causing the feed-belts to move and feed the tobacco onto the ledge Y and into the receiving-box U. As the treadle is raised and the quadrant returns to its normal 40 position the notch engages the lever Q², bringing it to its former position, the pawl N² sliding over the notches in the ratchet-wheel in an opposite direction, said wheel remaining at rest.

45 The quadrant l and its other connections will be described farther on.

D represents a raised frame attached to the table B, supporting a top and carrying the carriage H, having the bunching-roller X² 50 journaled therein, said carriage being moved by means of an arm attached to the quadrant l in connection with a bar similar to bar Q', already described, one end being connected to said arm, the other end passing through a 55 slot in table B and connecting with said carriage, as shown. Said arm has a spur projecting from its end, at right angles to which one end of the said connecting-bar is attached.

60 F is a bunching-apron having its opposite ends attached to the ends of the table supported by the frame D, having a slack in the middle to fall down into a cross-slot in the rolling-table, forming the pocket f.

65 E represents a mold-board containing matrices adapted to receive the cigar-bunches or cigars.

E' represents the carriage for the mold-board.

I represents the treadle, by means of which 70 the power is applied in operating the machine.

K represents a frame, which is attached to the ends of a vertical reciprocating cutter or knife S. Said knife moves up and down in 75 slots in the side of the upright frame R, having its ends extending through said frames, so that the ends of the frame K may pass over the ends of the knife, which is rounded to form journals, so that the ends of the 80 frame may move as a pitman thereon. The opposite end of the frame K is connected to the treadle I by means of the rod k by a washer and nut through a slot in treadle I, as shown at n.

L represents a chain, one end being connected to the edge or periphery of the quadrant l, and the other end connected with the treadle I.

It will be observed that the frame K is attached directly to the treadle by means of the rod k, as shown, and that consequently it must descend in unison with the treadle, and that so, also, the quadrant l must revolve or move on its center in unison with the treadle, 95 being connected, as described, by the chain L to said treadle.

The parts all being connected in the manner described and set forth, by pressing down the treadle the quadrant will immediately 100 begin to turn on its center. At the same time the lever Q², having its bifurcated end resting in a notch in the rim of the quadrant, will be actuated and pass out of the notch and remain at rest during the further downward 105 movement of the treadle. At the same time said lever, by reason of its connection with the part that carries the pawl N², will have actuated the ratchet-wheel N', which in turn will have moved the cog-wheels O², thus moving the feed-belts and feeding the tobacco. All this will take place on the first quarter 110 or first third of the downward movement of the treadle. On the return of the quadrant to its normal position the lever Q² will be 115 carried in the opposite direction, thus moving the pawl N² over the notches in the ratchet-wheel N', while said ratchet-wheel remains at rest, the bifurcated end of said lever falling 120 into said notch, as at first.

When the movement of the treadle and quadrant begins, as above described, and at the same time with said movement two other parts of the machine will be moved, as follows: The reciprocating cutter will begin to 125 descend; but as its movement is vertical to the treadle, and having direct connection thereto, it is much slower than the movement of the parts which feed the tobacco, and hence the knife performs its office during the last 130 third of the downward movement of the treadle, and in point of time long after the tobacco has been fed, the tobacco having been fed during the first third of the downward

movement, and, second, the movement of the frame H, with its bunching-roller, which begins with the downward movement of the treadle and the movement of the quadrant 5 and continues to pass over the frame D and the bunching-table in regular progression and so long as the quadrant moves in that direction. As soon as the pressure is removed from the treadle the weight or ball M on the 10 end of the lever m, being attached to the quadrant l, as shown, will raise the treadle and bring the parts back to their normal positions.

M is a weight or ball at the end of the lever m, said lever being connected to the quadrant l, 15 as shown.

We will now describe the receiving-box U, which is a device for receiving the tobacco from the feed-belts when severed by the cutter to be deposited in the pocket f.

20 The feed-box is composed of several separate parts adapted to operate together automatically. It extends across in front of the rollers X and X', presenting a perpendicular open side to the feed-belts, through which the 25 severed tobacco is delivered. It is secured in vertical ways, which are fastened in a suitable manner to the upright frames R. It rests upon yielding springs W, which are adapted to hold its bottom on a line with the cutting- 30 ledge Y, and it is adapted to be moved downward by pressure and slides in said vertical ways and is automatically returned to its normal position by the action of said springs. The feed-box has a front side, which is curved 35 near the bottom laterally downward and inward to meet the line of the open side and forming the bottom, the curved portion (or bottom) being formed by several longitudinal strips of metal, with edges hinged together and 40 adapted to move up or down in grooves in the end pieces of said box, said end pieces having the proper curve, so as to come on a line with said open side. The said movable bottom, composed of longitudinal strips hinged as described, we denominate the "shutter," and 45 designate it in the drawings by the letter U'.

The open side of the feed-box is adapted to be closed by means of the metallic slide S', and the cover is formed by means of the 50 wooden follower U², said slide and follower being attached as a cross-head to the lower end of the plunger V, by which they are operated. The plunger V and its cross-head, being part of the box, are described with said 55 box. Said plunger rests upon yielding springs W'. It is secured in vertical ways in a suitable manner to the upright frames R. It is operated by the handle V'. It is also adapted when pressed down to engage the box U and 60 carry it downward into the pocket f, so as to enable the severed tobacco to be deposited in said pocket. The springs W' rest upon lugs on the end pieces within the box U and are directly attached to the follower. 65 The plunger and the receiving-box are operated together by the independent action of the hand and not by the action of the treadle

and quadrant. The plunger having been pressed down, the metallic slide S' will close the open side of the box next to the feed-belts, the follower U² closing the top. The box being thus engaged will be carried down into the pocket f, and in the descent the lug v on the edge of the shutter U' will engage the lug v', thus opening said shutter, and the 70 tobacco is deposited in said pocket. The pressure now being removed, the springs W and W' raise the box and plunger to their 75 normal positions, and in the ascent the lug v engages the cross-bar v² and closes the 80 shutter.

U' is the shutter composing the bottom of the box U.

V is the plunger.

V' is the handle of plunger.

e represents a rod attached to the pawl e², adapted to raise said pawl, when pushed, in order to enable the carriage E' to be lowered.

We will now describe the operation of the bunching-apron F in connection with the bunching-roller X² in the carriage H'. Said apron, as already described, falls down in a cross-slot in the rolling-table, forming a pocket, and as said roller X² is made to advance over the frame D and table the sides of the 90 apron at the top of the pocket are brought together, being slightly raised by the spring f', and the apron passes double under the roller, forming a bight. As the roller advances, the pocket is raised out of the cross-slot in the 95 table, the bight being continually shortened as the roller advances until the bight will entirely disappear. The tobacco, being now under the apron at the matrix, will be forced into the mold by the said roller as the slack 100 of the apron disappears, and on the return of the roller the apron will fall into its normal position.

We will now describe the manner and mode of packing the tobacco and placing it between the feed-belts. It has already been seen that the mechanism denominated the "packer" consists, essentially, of two parts G and G', one end being closed, the end piece being secured in the bottom half G, so that the cover 110 G' is free to slide over it. To begin the packing, the cover G' is slid longitudinally nearly off from the bottom G—say to within two inches of the closed end—and the leaf-to-bacco is broken across bottom G from side to 115 side and carefully packed in the space between the bottom and cover back to the end piece, cover G' being advanced as the packing progresses, the filling always running crosswise of the packer and lengthwise of the 120 leaf until the packer is entirely filled. The frame C should now be raised and stood up out of the way and the packer turned upon its hinges and laid over upon the lower feed-belt G² in the frame C', the cover G' being 125 under and next to the belt. Cover G' is then slipped longitudinally from beneath and bottom G is turned back, leaving the tobacco 130 upon the belt. Now bring down the frame C

and the tobacco will be held between the feed-belts.

We will now follow the tobacco and explain the process in placing the rolled cigar or cigar-bunch in the matrices. Press down the treadle I and the tobacco will be fed onto the cutting-ledge Y and into the receiving or feed box U and severed by the vertical reciprocating cutter S, as described. The pressure being removed from the treadle, the weight M brings all the parts back to their normal positions. The plunger V is then pressed down by hand and the severed tobacco in the receiving or feed box is deposited in the pocket f, and said box and plunger are allowed to come back to their normal positions, as described. The operator now places a binder upon the rolling-apron slightly in front of the pocket f and again presses down the treadle. This time the severed tobacco in the pocket will be rolled and deposited in the matrix, as described, and the tobacco between the feed-belts will have been fed and severed, as before. The operator now deposits the severed tobacco in the pocket by pressing down the plunger and places a binder upon the rolling-apron, as described, and presses down the treadle, and so alternately operating the parts, first the plunger and receiving-box, then the treadle until all the tobacco between the belts has been rolled, the carriage E' being raised each time the treadle makes a downward movement, so as to present a matrix for the cigar or cigar-bunch.

Having fully described our invention, what we claim as new, and desire to secure by Letters Patent, is—

1. In a cigar-bunching machine, the combination of the frames having belt-supporting rollers, the upper one being adapted to be elevated, the feeding-belts arranged upon the rollers, the packer arranged to have its contents dumped upon the lower feed-belt, a reciprocating cutter, the vertically-moving receiving-box, the follower in said box, the sliding shutter, and means, substantially as described, for opening and closing the shutter.

2. The combination of the packer, suitable feeding-belts, a reciprocating cutter, the vertically-moving receiving-box having a vertically-sliding bottom or shutter guided in its

side slots, and means for elevating the box and for operating the shutter, the apron, and the bunching-roller, as set forth.

3. The combination of the packer having a sliding cover, the device conforming in cross-section to the contour of a cigar, suitable feed-belts, the upper one being carried by a pivoted frame, a cutter at the inner end of the feed-belts, a vertically-sliding receiving-box having an independent and vertically-sliding bottom or shutter, a follower, a slide arranged as set forth, and suitable bunch-rolling mechanism.

4. A receiving-box for a cigar-machine, arranged to slide vertically after receiving its charge, consisting, essentially, of three principal parts, constituting the receptacle, the side parts provided with vertical and curved guide-slots, a jointed sliding bottom arranged in the slide-slots, in combination with means for elevating the box and independent and separate means for opening and closing the bottom, as set forth.

5. The combination of the vertically-reciprocating receiving-box U, having the independent sliding bottom U', the parts u of which are jointed and adapted to slide in the curved guide-slots of the box, the follower in the box, means for elevating the box, means for opening and closing the bottom, a rolling-apron, a reciprocating bunching-roller, and a mold E, arranged as described.

6. The combination of the feed-belts arranged on frames C C', the former being vertically adjustable and articulated, a packer having a sliding cover and of a contour in cross-section to that of a cigar, a vertically-sliding cutter, the vertically-sliding receiving-box U, having a sliding bottom U', a follower in the box, a slide for closing the open side of the box, means for elevating the box and opening and closing the bottom independently thereof, the apron, a bunching-roller, and the mold, as set forth.

In testimony whereof we affix our signatures in presence of two witnesses.

GEORGE L. WESTMAN.
JOSEPH DELARUE.
